UNITED STATES PATENT OFFICE.

LEE F. DUFF AND GEORGE LANGHANS, OF LOS ANGELES, CALIFORNIA.

DESIGN FOR A ROTARY DISPLAY CASE.

Application filed July 18, 1923. Serial No. 6,794. Term of patent 14 years.

To all whom it may concern:

Be it known that we, LEE F. DUFF and GEORGE LANGHANS, citizens of the United States, residing at Los Angeles, in the county of Los Angeles and State of California, have invented a new, original, and ornamental Design for Rotary Display Case, of which the following is a specification, reference being had to the accompanying drawing, forming part thereof.

In the drawing:

Fig. 1 is an elevational view of the rotary display case.

Fig. 2 is a section taken on line 2—2 of Fig. 1.

We claim:

The ornamental design for a rotary display case, as shown.

LEE F. DUFF.
GEORGE LANGHANS.

Witness:

VIRGINIA M. ARCLEED,
